UNITED STATES PATENT OFFICE.

ARTHUR MIDDLETON ROSE, OF YONKERS, NEW YORK, ASSIGNOR TO
WILLIAM H. McCALLUM AND IRVING McCALLUM, OF PHILADEL-PHIA, PENNSYLVANIA.

DESIGN FOR CARPET.

SPECIFICATION forming part of Design No. 29,010, dated July 5, 1898.

Application filed June 3, 1898. Serial No. 682,500. Term of patent 3½ years.

To all whom it may concern:

Be it known that I, ARTHUR MIDDLETON ROSE, a citizen of the United States, residing at the city of Yonkers, in the county of Westchester and State of New York, have invented and produced a new and original Design for a Carpet or other Fabric, of which the following is a specification, reference being had more particularly to the accompanying drawing, illustrating the same and forming part hereof.

The leading feature of my design is a chintz pattern of roses and vines scattered over a suitable ground.

In the drawing, a is the body, b the border, and a b the complete carpet.

c are roses.

d are vines, and e is the ground. What I claim as my invention, and desire to secure by Letters Patent, is—

1. In a design for a carpet, the body a, substantially as described and shown.
2. In a design for a carpet, the border b, substantially as described and shown.
3. The design for a carpet consisting of the body a, and border b, substantially as described and shown.

In testimony whereof I have hereunto signed my name.

ARTHUR MIDDLETON ROSE.
